UNITED STATES PATENT OFFICE.

JOSEPH FORCIER, OF BREMERTON, WASHINGTON.

LIFE-BOAT ATTACHMENT.

1,171,602.

Specification of Letters Patent.

Patented Feb. 15, 1916.

Application filed May 14, 1915. Serial No. 28,237.

To all whom it may concern:

Be it known that I, JOSEPH FORCIER, a citizen of the United States, residing at Bremerton, in the county of Kitsap and State of Washington, have invented new and useful Improvements in Life-Boat Attachments, of which the following is a specification.

This invention relates to life saving apparatus and more particularly to apparatus for raising, lowering and releasing life boats.

One of the principal objects of the invention is to provide a novel type of raising and lowering winch which may be shifted about over the deck of the vessel and which will take care of both davit cables whereby simultaneous action of these cables is assured.

Another object of the invention is to provide a simple and efficient releasing mechanism whereby both davit cables may be simultaneously released from the boat when lowered and which mechanism is so constructed that it may be operated by a single man.

Further objects of the invention will appear as the following specific description is read in connection with the accompanying drawings which form a part of this application and in which:

Figure 1 is a top plan view showing the arrangement of the raising and lowering mechanism; Fig. 2 is a rear elevation of the raising and lowering mechanism on a somewhat enlarged scale; Fig. 3 is a detail sectional view taken on the line 3—3 of Fig. 1; Fig. 4 is a detail top plan view of the boat; Fig. 5 is a longitudinal section therethrough; Fig. 6 is a vertical sectional view taken on the line 6—6 of Fig. 5; Fig. 7 is a similar view taken on the line 7—7 of Fig. 5, and Fig. 8 is an enlarged top plan view of the winch.

Referring more particularly to the drawings 1 represents the deck of the vessel, in this instance shown provided with a pair of bolt supporting bolsters 2 upon which the lift boat 3 of any suitable construction is adapted to rest when not in use. These bolsters have connected thereto lashing of any preferred type but preferably of the type shown and indicated at 4.

Mounted upon the deck for free-swinging movement are the usual davits 5 carrying the pulleys 6 and 7 over which the cables 8 and 9 are adapted to pass, each cable being provided at one terminal with suitable hooks

10. The cables 8 and 9 also pass over the pulleys 11 secured to the deck.

Before proceeding to describe the winch construction, I shall first thoroughly describe the construction of the releasing mechanism which is carried by the boat. Secured to the bow and stern pieces are brackets 12 having pivotally mounted thereon the hook engaging pins 13 whose free ends are retained in operative position by the yoke members 14 and 15 also pivoted in the brackets. These yoke members are arranged to engage over the free ends of the pins so that they are held in horizontal position and are operated in the following manner: Extending longitudinally of the boat and mounted between certain of the thwarts or cross braces is a supporting beam 16 upon which is pivoted a lever 17 the pivot bolt passing through the lever intermediate its ends as is shown. Connected to the lever above its pivotal point and to the yoke member 14 is a connecting link 18 and connected to the lever 17 below its pivotal point and to the yoke member 15 is an actuating rod 19 which extends between the thwarts and is mounted in suitable bearings carried thereby. The lever 17 is provided with a painter adapted to actuate the lever for releasing both yoke members 14 and 15 from the hook engaging pins or fingers 13 simultaneously. This construction obviates the employment of a man at each end of the boat for releasing the cable hooks from the usual eyes which project above the deck.

To properly actuate the cables 8 and 9 in raising and lowering the boat there is provided a winch of novel type consisting of a base 20 mounted upon supporting wheels 21 so as to be readily moved about the deck. Mounted upon the base are separate paths of bearing brackets or frames 22 and rotatably mounted in each bearing is a drum shaft 23 which is driven through a crank shaft 24 geared to the drum shaft as shown. Both of the drum shafts 23 are connected to the cables 8 and 9 in any suitable manner and these shafts extend in a plane normal to the line of the cable and are connected together in their inner ends by a universal joint 25. Each drum shaft has secured thereon a brake drum 26 over which extends a flexible brake band 27 secured at one end to the base or platform 20 and at the opposite end to one leg of a V-shaped brake beam

28, the free ends of which are pivoted to the base. Passed through the apex 28 of the brake beam is an adjusting screw 29 which is swiveled to the base and has threaded thereon the hand wheel 30 as shown. By manipulation of the hand wheel both brake bands may be tightened or loosened to control the speed of descent of the boat as will be readily understood. By applying pressure to both brake drums simultaneously the strain is entirely removed from the universal joint and a more uniform lowering may be had. By providing a portable winch of this character, as one boat is lowered the winch 10 may be readily moved to other boats on the deck or where the boats are arranged in groups or on skids the winch may be anchored to the deck in any suitable manner.

What is claimed is:

20. 1. In life saving apparatus, the combination with boat davits and cables therefor of means for operating the cables comprising a portable base, cable drums mounted thereon and arranged at an angle to each other, 25 means for simultaneously operating said drums, brakes therefor and a common controlling means for the brakes.
2. In life saving apparatus, the combination with boat davits and cables therefor, of

winding mechanism for the cables comprising a portable base, angularly positioned drum shafts, means for connecting the drum shafts for simultaneous operation, operating means for the drum shafts, separate brake bands for said shafts, a lever common to both bands and means for actuating the lever.

3. In life saving apparatus, the combination with boat davits and cables therefor, of means for winding and unwinding the cables comprising angularly positioned shafts universally connected together, a brake for each shaft, a V-shaped lever connected to the brakes and an operating device for the lever.

4. In a life-saving apparatus, the combination with boat davits and cables therefor, of means for winding and unwinding the cables comprising angularly positioned shafts universally connected together, a brake for each shaft, an operating lever common to both brakes and means for operating the lever to apply the brake.

In testimony whereof I affix my signature in presence of two witnesses.

JOSEPH FORCIER.
